HOLDER FOR DISK-TYPE PHONOGRAPH RECORDS

Wilson Daymon, Hamden, Conn.

Application March 1, 1947, Serial No. 731,840

12 Claims. (Cl. 206—62)

1

The present invention relates to improvements in holders for phonograph records and relates more particularly to improvements in holders for phonograph records of the disk type.

Heretofore, it has been a general practice to provide record-holders in the form of albums having a plurality of hinged and apertured envelopes, each of which is adapted to hold an individual disk-type record.

The individual envelopes referred to are not only expensive as to materials but also as to the labor required for their hinged securement in an album or other holder.

One of the main objects of the present invention is to provide a superior holder for disk-type records which may be produced at a low cost for manufacture.

Another object of the present invention is to provide a superior holder of the character referred to which is sufficiently strong to withstand rough usage in shipment, as well as being convenient for use.

A further object of the present invention is to provide a superior holder of the character referred to which will securely hold a plurality of disk-records in such manner as not to injure their sound-recording faces and in such manner as to prevent their displacement in any radial direction.

Still another object of the present invention is to provide a superior record-holder of the character referred to which will securely hold a plurality of disk-type records when desired, but which will readily release such records for convenient removal from the holder.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is an edge view of a record-holder in the form of an album and constructed in accordance with the present invention;

Fig. 2 is a face view thereof with the front cover of the album broken away and with a plurality of records shown as clamped within the record-holding band;

Fig. 3 is a broken detail sectional view taken on the line 3—3 of Fig. 2;

Fig. 4 is a similar view taken on the line 4—4 of Fig. 2;

Fig. 5 is a view similar to Fig. 2 but showing the record-holding band expanded to release the records; and

Fig. 6 is a broken perspective view of the portions of the structure adjacent the operating lever.

2

The particular record-holder chosen for illustration in the accompanying drawings for purposes of making clear a preferred form of the present invention, includes an album proper generally designated by the reference character 10 and which comprises a plate-like front cover 11 and a back cover 12. The said covers are respectively hinged at 13 and 14 to an end-spacer 15. The parts 11, 12 and 15 may be conveniently formed of heavy cardboard and may be hinged together in a manner common in the art such, for instance, as by suitably scoring or cutting the cardboard and covering the joints with flexible material such as cloth. In some instances it has been found convenient to employ sheet aluminum for the parts 11, 12 and 15.

Secured to the inner face of the back cover 12 or other suitable mounting-member in a manner as will more fully hereinafter appear, is a laterally expansible and contractible record-holding band generally designated by the reference character 16 and which may be conveniently formed of sheet steel, aluminum, brass, synthetic resin, or other flexible material.

At its edge, adjacent the back cover 12, the record-holding band 16 is provided with five (more or less) circumferentially spaced and apertured fingers 17, 18, 19, 20 and 21 located adjacent the inner face of the said back cover 12.

The respective terminal-ends 22 and 23 of the record-holding band 16 are preferably circumferentially separated to provide a finger-clearance gap 24 for purposes as will hereinafter appear. In the instance shown, the flange-like fingers 20

35 and 21 are respectively rigidly secured to the back cover 12 by fastening-means in the form of rivets 25 and 26 or their equivalent extending through the said fingers and having their heads overlying the same. The flange-like fingers 17 and 19 are respectively provided with slots 27 and 28 which serve to permit the adjacent portion of the band 16 to be expanded and contracted in lateral directions toward and away from the peripheries of a plurality of disk-type records

40 stacked in face-to-face relationship and laterally encircled by the said band, as is especially well shown in Fig. 2.

Rigidly mounted in the back cover 12 and respectively extending through the slots 27 and 28 of the fingers 17 and 19 are rivet-like studs 30 and 31 having their heads respectively overlying the adjacent portions of the respective fingers 17 and 19.

Pivoted by means of a rivet 32 to the portion 55 of the finger 17 immediately adjacent the terminal-end 22 of the band 16 is one end of a link 33 which is preferably curved as shown, to substantially conform to the curvature of the band 16 when the same is in its clamped position. The end of the link 33 opposite the rivet 32 is piv-

60

totally connected by means of a rivet 34 to an intermediate portion of an operating-lever 35 which is also preferably curved to substantially correspond to the curvature of the adjacent portion of the band 16 when the latter is contracted, as is indicated in Fig. 2.

One end of the operating-lever 35 is pivotally connected by means of a rivet 36 to the outwardly-extending finger 18 of the band 16 at a point immediately adjacent the terminal-end 23 of the said band. The end of the operating-lever 35 opposite the rivet 36, is bent upwardly or otherwise provided with a finger-piece 31 by means of which the said lever may be swung about the said rivet 36 as a center.

The upper or outer edge of the record-holding band 16 is bent inwardly or otherwise provided with three (more or less) inwardly-projecting retaining-flanges or -abutments 38, 39 and 40, each of which is adapted to overlie the adjacent rim-portion of the uppermost of the stack of disk records 29.

Preferably, the parts are so proportioned that when the operating-lever 35 is swung into the position in which it is indicated in Figs. 1 and 2, it will draw the record-holding band 16 snugly around the peripheries of the stack of records 29 and will cause the rivet 34 to pass slightly inwardly beyond a line connecting the rivet 32 and the rivet 36, to thus locate the rivet 34 in a position past "dead center." By this construction and arrangement of parts, the operating-lever 35 is automatically held in the position in which it is shown in Figs. 1 and 2, by any force tending to expand the band 16.

When the operating-lever 35 is swung by means of its finger-piece 31 from the position in which it is shown in Figs. 1 and 2 into the position in which it is shown in Fig. 5, the finger-clearance gap 24 will be widened and the portions of the band intermediate the terminal-end 22 and finger 21 and intermediate the terminal-end 23 and the finger 20 will be shifted laterally outwardly into substantially the positions shown in Fig. 5.

The respective end-portions of the band 16 will be guided in their lateral outward movement by the coaction of the studs 30 and 31 with the surfaces of the slots 27 and 28, while at the same time the said studs will also maintain the band against edgewise movement away from the back cover 12 or its equivalent.

The record-holding band 16 will be held in its expanded position by operating-lever 35 and the link 33, since the rivet 34 will have passed dead-center with respect to the rivets 32 and 36 when the parts reach the position in which they are shown in Fig. 5.

With the record-holding band 16 expanding into the position in which it is shown in Fig. 5, the retaining flanges 38 and 39 will be moved outwardly clear of the periphery of the stack of records 29, whereupon the user may insert one of his fingers through the finger-clearance gap 24 and tilt up the adjacent portion of the top-most record 29, following which such record may be removed by drawing the same edgewise over the retaining-flanges 38 and 39 and out from beneath the retaining-flange 40.

When it is desired to return the records such as 29 into the holder, the procedure above described for the removal may be reversed, following which the operating-lever 35 may be moved back into the position in which it is shown in Fig. 2 to thereby laterally contract the record-

holding band 16 into the position in which it is shown in Fig. 2.

When the record-holding band 16 is "clamped," so to speak, around the peripheries of the group of records installed in its interior, such records will be restrained against flatwise movement in all directions and will be retained against displacement away from the back cover 12 or its equivalent by means of the retaining-flanges or -abutments 38, 39 and 40. The holding of the records will stand firm against even rough handling of the record-album 10, all without injury to the recording surfaces of said records.

The record-holding band 16 or its equivalent 15 may be formed of spring metal and may, if desired, be pre-tensioned, so as to tend to expand toward the position in which it is indicated in Fig. 5.

The invention may be carried out in other 20 specific ways than those herein set forth without departing from the spirit and essential characteristics of the invention, and the present embodiments are, therefore, to be considered in all respects as illustrative and not restrictive, and all changes coming within the meaning and equivalency range of the appended claims are 25 intended to be embraced therein.

I claim:

1. A holder for disk-type phonograph records, 30 including in combination: a mounting-member; a laterally-expansible-and-contractible record-holding band of substantially-annular form shaped to substantially laterally enclose a plurality of disk records and having its width extending substantially perpendicular with respect to the said mounting-member; connecting-means connecting the said record-holding band to the said mounting-member against displacement with respect thereto and constructed and arranged to permit the said band to expand and contract in a lateral direction; and manually-operable band-contracting means operatively connected to the said record-holding band and constructed and arranged to contract the same laterally toward the periphery of a plurality of disk records within the said band to restrain the said disk records against displacement with respect to the said mounting-member.

2. A holder for disk-type phonograph records, 50 including in combination: a mounting-member; a laterally-expansible-and-contractible record-holding band of substantially-annular form having its ends spaced from each other to provide a finger-clearance gap and shaped to substantially laterally enclose a plurality of disk records and having its width extending substantially perpendicular with respect to the said mounting-member; connecting-means connecting the said record-holding band to the said mounting-member against displacement with respect thereto and constructed and arranged to permit the said band to expand and contract in a lateral direction; and manually-operable band-contracting means operatively connected to the 55 respective opposite end-portions of the said record-holding band to laterally contract the same toward the periphery of a plurality of disk records within the said band to restrain the said disk records against displacement with respect to the said mounting-member.

3. A holder for disk-type phonograph records, 60 including in combination: a mounting-member; a laterally-expansible-and-contractible record-holding band of substantially-annular form shaped to substantially laterally enclose a plu-

rality of disk records and having its width extending substantially perpendicular with respect to the said mounting-member; retaining-means carried by the said band and projecting inwardly therefrom in spaced relationship with respect to the said mounting-member in position to overlie disk records within the said band; connecting-means connecting the said record-holding band to the said mounting-member against displacement with respect thereto and constructed and arranged to permit the said band to expand and contract in a lateral direction; and manually-operable band-contracting means operatively connected to the said record-holding band and constructed and arranged to laterally contract the same toward the periphery of a plurality of disk records within the said band to restrain the said disk records against displacement with respect to the said mounting-member.

4. A holder for disk-type phonograph records, including in combination: a mounting-member; a laterally-expansible-and-contractible record-holding band of substantially-annular form having its ends spaced from each other to provide a finger-clearance gap and shaped to substantially laterally enclose a plurality of disk records and having its width extending substantially perpendicular with respect to the said mounting-member; retaining-means carried by the said band and projecting inwardly therefrom in spaced relationship with respect to the said mounting-member in position to overlie disk records within the said band; connecting-means connecting the said record-holding band to the said mounting-member against displacement with respect thereto and constructed and arranged to permit the said band to expand and contract in a substantially-radial direction; and manually-operable band-contracting means operatively connected to the respective opposite end-portions of the said record-holding band and constructed and arranged to contract the same in a substantially-radial direction toward the periphery of a plurality of disk records within the said band to restrain the said disk records against displacement with respect to the said mounting-member.

5. A holder for disk-type phonograph records, including in combination: a mounting-member; a laterally-expansible-and-contractible record-holding band of substantially-annular form shaped to substantially laterally enclose a plurality of disk records and having its width extending substantially perpendicular with respect to the said mounting-member; retaining-means carried by the said band and projecting inwardly therefrom in spaced relationship with respect to the said mounting-member in position to overlie disk records within the said band; connecting-means connecting the said record-holding band to the said mounting-plate against displacement with respect thereto and including a plurality of circumferentially-spaced apertured fingers carried by the said band and projecting laterally therefrom adjacent the said mounting-member, and a plurality of fastening-members carried by the said mounting-member and respectively extending through the said fingers, certain of the said fastening-members adjacent the hereinafter-mentioned band-contracting means loosely fitting the apertures in the fingers through which they extend to permit the adjacent portions of the band to move laterally and others of the said fastening-members remote from the said band-contracting means serving to relatively tightly hold the fingers through which they extend; and man-

ually-operable band-contracting means operatively connected to the said record-holding band and constructed and arranged to laterally contract the same toward the periphery of a plurality of disk records within the said band to restrain the said disk records against displacement with respect to the said mounting-member.

6. A holder for disk-type phonograph records, including in combination: a mounting-member; a laterally-expansible-and-contractible record-holding band of substantially-annular form having its ends spaced from each other to provide a finger-clearance gap and shaped to substantially laterally enclose a plurality of disk records and having its width extending substantially perpendicular with respect to the said mounting-member; retaining-means carried by the said band and projecting inwardly therefrom in spaced relationship with respect to the said mounting-member in position to overlie disk records within the said band; connecting-means connecting the said record-holding band to the said mounting-plate against displacement with respect thereto and including a plurality of circumferentially-spaced apertured fingers carried by the said band and projecting laterally therefrom adjacent the said mounting-member, and a plurality of fastening-members carried by the said mounting-member and respectively extending through the said fingers, certain of the said fastening-members adjacent the hereinafter-mentioned band-contracting means loosely fitting the apertures in the fingers through which they extend to permit the adjacent portions of the band to move laterally and others of the said fastening-members remote from the said band-contracting means serving to relatively tightly hold the fingers through which they extend; and manually-operable band-contracting means operatively connected to the respective opposite end-portions of the said record-holding band and constructed and arranged to laterally contract the same toward the periphery of a plurality of disk records within the said band to restrain the said disk records against displacement with respect to the said mounting-member.

7. A holder for disk-type phonograph records, including in combination: an album having a first cover and a second complementary cover; a laterally-expansible-and-contractible record-holding band of substantially-annular form shaped to substantially laterally enclose a plurality of disk records and having its width extending substantially perpendicular with respect to the said covers when the same are closed; connecting-means connecting the said record-holding band to the said first cover against displacement with respect thereto and constructed and arranged to permit the said band to expand and contract in a lateral direction; and manually-operable band-contracting means operatively connected to the said record-holding band to laterally contract the same toward the periphery of a plurality of disk records within the said band to restrain the said disk records against displacement with respect to the said first cover.

8. A holder for disk-type phonograph records, including in combination: an album having a first cover and a second complementary cover; a laterally-expansible-and-contractible record-holding band of substantially-annular form and having its ends spaced from each other to provide a finger-clearance gap and shaped to substantially laterally enclose a plurality of disk records and having its width extending substan-

tially perpendicularly with respect to the said covers when the same are closed; connecting-means connecting the said record-holding band to the said first cover against displacement with respect thereto and constructed and arranged to permit the said band to expand and contract in a lateral direction; and manually-operable band-contracting means operatively connected to the respective opposite end-portions of the said record-holding band to laterally contract the same toward the periphery of a plurality of disk records within the said band to restrain the said disk records against displacement with respect to the said first cover.

9. A holder for disk-type phonograph records, including in combination: an album having a first cover and a second complementary cover; a laterally-expansible-and-contractible record-holding band of substantially-annular form shaped to substantially laterally enclose a plurality of disk records and having its width extending substantially perpendicularly with respect to the said covers when the same are closed; retaining-means carried by the said band and projecting inwardly therefrom in spaced relationship with respect to the said first cover in position to overlie disk records within the said band; connecting-means connecting the said record-holding band to the said first cover against displacement with respect thereto and constructed and arranged to permit the said band to expand and contract in a lateral direction; and manually-operable band-contracting means operatively connected to the said record-holding band and constructed and arranged to laterally contract the same toward the periphery of a plurality of records within the said band to restrain the said records against displacement with respect to the said first cover.

10. A holder for disk-type phonograph records, including in combination: an album having a first cover and a second complementary cover; a laterally-expansible-and-contractible record-holding band of substantially-annular form having its ends spaced from each other to provide a finger-clearance gap and shaped to substantially laterally enclose a plurality of disk records and having its width extending substantially perpendicularly with respect to the said covers when the same are closed; retaining-means carried by the said band and projecting inwardly therefrom in spaced relationship with respect to the said first cover in position to overlie disk records within the said band; connecting-means connecting the said record-holding band to the said first cover against displacement with respect thereto and constructed and arranged to permit the said band to expand and contract in a lateral direction; and manually-operable band-contracting means operatively connected to the respective opposite end-portions of the said record-holding band and constructed and arranged to laterally contract the same toward the periphery of a plurality of records within the said band to restrain the said records against displacement with respect to the said first cover.

11. A holder for disk-type phonograph records, including in combination: an album having a first cover and a second complementary cover; a laterally-expansible-and-contractible record-holding band of substantially-annular form shaped to

substantially laterally enclose a plurality of disk records and having its width extending substantially perpendicularly with respect to the said covers when the same are closed; retaining-means carried by the said band and projecting inwardly therefrom in spaced relationship with respect to the said first cover in position to overlie disk records within the said band; connecting-means connecting the said record-holding band to the said first cover against displacement with respect thereto and including a plurality of circumferentially-spaced apertured fingers carried by the said band and projecting laterally therefrom adjacent the said first cover, and a plurality of fastening-members carried by the said first cover and respectively extending through the said fingers, certain of the said fastening-members adjacent the hereinafter-mentioned band-contracting means loosely fitting the apertures in the fingers through which they extend to permit the adjacent portions of the band to move laterally and others of the said fastening-members remote from the said band-contracting means serving to relatively tightly hold the fingers through which they extend; and manually-operable band-contracting means operatively connected to the said record-holding band and constructed and arranged to laterally contract the same toward the periphery of a plurality of records within the said band to restrain the said records against displacement with respect to the said first cover.

12. A holder for disk-type phonograph records, including in combination: an album having a first cover and a second complementary cover; a laterally-expansible-and-contractible record-holding band of substantially-annular form having its ends spaced from each other to provide a finger-clearance gap and shaped to substantially laterally enclose a plurality of disk records and having its width extending substantially perpendicularly with respect to the said covers when the same are closed; retaining-means carried by the said band and projecting inwardly therefrom in spaced relationship with respect to the said first cover in position to overlie disk records within the said band; connecting-means connecting the said record-holding band to the said first cover against displacement with respect thereto and including a plurality of circumferentially-spaced apertured fingers carried by the said band and projecting laterally therefrom adjacent the said first cover, and a plurality of fastening-members carried by the said first cover and respectively extending through the said fingers, certain of the said fastening-members adjacent the hereinafter-mentioned band-contracting means loosely fitting the apertures in the fingers through which they extend to permit the adjacent portions of the band to move laterally and others of the said fastening-members remote from the said band-contracting means serving to relatively tightly hold the fingers through which they extend; and manually-operable band-contracting means operatively connected to the respective opposite end-portions of the said record-holding band and constructed and arranged to laterally contract the same toward the periphery of a plurality of records within the said band to restrain the said records against displacement with respect to the said first cover.
